UNITED STATES PATENT OFFICE.

VAUGHN STODDARD, OF CHELSEA, IOWA.

MACHINE-GUN.

1,242,068.

Specification of Letters Patent. Patented Oct. 2, 1917.

Application filed November 13, 1916. Serial No. 131,070.

To all whom it may concern:

Be it known that I, VAUGHN STODDARD, a citizen of the United States, residing at Chelsea, in the county of Tama and State 5 of Iowa, have invented a new and useful Machine-Gun, of which the following is a specification.

The present invention appertains to machine or rapid fire guns, and aims to provide a novel and improved gun for firing 10 the shells in rapid succession in a practical and efficient manner.

One of the objects of the invention is the provision of novel means for supplying the 15 shells to the gun, the structure embodying shell holding means of large capacity, yet compact and simple in construction.

Another object of the invention is to provide novel and effective means for inserting 20 the shells from the shell feeding means into the rifle bores of the rotatable multi-bore barrel, for locking the shells in place when inserted and during the firing thereof, and for then ejecting or withdrawing the shells 25 when empty.

A further object of the invention is the provision of novel means for firing the shells.

A still further object of the invention is 30 the provision of novel means for cooling the barrel.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 35 within the scope of what is claimed without departing from the spirit of the invention.

The invention is illustrated in the accompanying drawings, wherein:

Figure 1 is a plan view of the gun, a portion of the magazine cover or lid being broken away.

Fig. 2 is a side elevation thereof.

Fig. 3 is a rear view.

Fig. 4 is an enlarged rear end view of the breech loading mechanism.

Fig. 5 is a plan view of said mechanism, portions being broken away and shown in section.

Fig. 6 is a section on the line 6—6, of Fig. 2 illustrating the feed chain.

Fig. 7 is an enlarged section on the line 7—7 of Fig. 6.

Fig. 8 is a fragmental detail of the magazine.

Fig. 9 is an enlarged perspective view of one link or block of the chain.

Fig. 10 is a fragmental side elevation of the breech end of the barrel.

Fig. 11 is a longitudinal section of one 65 of the shell inserters and ejectors and its firing pin.

Fig. 12 is an end view, taken from the rear, of the device shown in Fig. 11.

Fig. 13 is a forward end view of the device shown in Fig. 11.

In carrying out the invention, there is provided a rotatable hollow or tubular barrel 1 having disposed thereon between its ends a split collar 2, while the breech end of the barrel is rotatable within a split sleeve 3, upper and lower longitudinal bars 4 being clamped between the upper and lower ends of the sections of the collar 2 and sleeve 3 to strengthen the structure.

A suitable telescopic sight 5 is mounted upon the barrel or upper bar 4, and the gun is provided with a suitable shield 6 for protecting the vital parts and operator and attendants.

The collar 2 is trunnioned between a pair of standards 7 mounted for rotation about a vertical axis upon a base 8, and the collar 2 being trunnioned between the standards 7 permits the barrel to be swung about a horizontal axis as well as a vertical axis to properly aim the gun. A suitable device 9 is employed for turning the standards 7 upon the base about a vertical axis, while a suitable device 10 is used for raising and 95 lowering the sleeve 3. A seat 11 is carried by the base in rear of the barrel for supporting the operator.

The chamber 12 of the barrel 1 is closed at its ends, and water circulating pipes 13 and 14 extend through the ends of the barrel centrally thereof, to permit the barrel to rotate while the pipes stand still, suitable packing means being provided to prevent leakage. Water or other cooling liquid is 100 delivered into the barrel from one pipe and is carried out by way of the other, and the cool water in being delivered into the barrel will cool the walls thereof, thereby avoiding excessive heat which would be apt 110 to put the gun out of commission.

The barrel 1 is provided in its walls with

an annular series of longitudinal rifle bores 15 extending from the forward or muzzle end of the barrel to an annular groove or recess 16 with which the barrel is provided 5 at its breech end. The barrel and sleeve 3 are provided with complementing annular ball races 17 in which anti-frictional balls 18 work, whereby the barrel can rotate freely with minimum friction.

10 The groove 16 provides in rear thereof an annular collar 19 which carries the devices for inserting the shells in the rifle bores 15, for locking the shells in the bores, and for withdrawing or ejecting the shells 15 after firing. For this purpose, the collar 19 is provided with an annular series of longitudinal bores 20 alining with the rifle bores 15, and longitudinal tubular shell inserting and ejecting members 21 are slidable 20 in the bores 20 and are of greater length than said bores. Each member 21 is provided between its ends with opposite longitudinal feathers 22 of limited length, and each bore 20 has an enlargement 24 between 25 its ends, and a pair of channels or featherways 23 extending from the enlargement 24 to the rear face of the collar 19. When the members 21 are drawn rearwardly, the feathers 22 slide within the channels 23, 30 thereby preventing the turning of the members 21 in their bores 20, but permitting said members to be slid longitudinally. When the members 21 are forced forwardly to bring the feathers 22 within the chambers 35 or enlargements 24, the members 21 can be turned or rotated thereby moving the feathers 22 out of alinement with their channels 23 and bringing the rear ends of the feathers 22 against the shoulders formed by the rear 40 ends of the enlargements 24, to lock the members 21 in place and prevent the rearward movement thereof.

A firing pin 25 is slidable within each member 21, and is provided with a reduced forward end 26, slidable through the forward end of the member 21 and projectible therefrom for denting and firing the shell. The forward end of each member 21 has an arcuate hook-shaped shell ejecting or withdrawing lip 27 for receiving the ejecting flange or bead of the shell. Each member 21 has a counter bore 28 extending from its rear end and in which a collar or enlargement 29 of the firing pin 25 is slidable, a coiled wire 55 expansion spring 30 surrounding said pin within the counter bore 28 and being confined between the shoulder formed by the counter bore and the collar 29 to normally retract the firing pin rearwardly, as seen in 60 Fig. 11. The rear terminal of the firing pin is slidable through a bushing 31 threaded into or otherwise engaged to the rear end of the member 21.

In order that each member 21 can be 65 properly reciprocated and oscillated, it is

provided near its rear end with an enlargement 32 to which opposite rollers 33 are pivoted, and a transverse member 34 is hinged or pivoted, as at 35, to the enlargement 32 at the rear side thereof, and carries a pair 70 of opposite rollers 36. The rollers 33 are for the purpose of reciprocating the member 21, while the rollers 36 are for the purpose of oscillating or turning said member, as will hereinafter more fully appear. When the members 21 are drawn rearwardly, only the lips 27 thereof project forwardly from the collar 19, for the reception of the ejector flange of the shells, and when the members 21 are moved forwardly, they are projected 80 across the groove 16, as seen in Fig. 5.

The mechanism for feeding the shells to the barrel, includes an endless feed chain 37 composed of the links or blocks 38 having the hinge butts 39 pivotally connected with 85 one another. The links 38 are hinged together at their inner sides, and are also provided with rollers 41 projecting from their outer sides to assist in guiding the links properly. Each link 38 is provided in its 90 inner side with a transverse recess or groove 42 for receiving a shell.

The feed chain 37 is movable within and along a U-shaped guide 43 having its limbs disposed horizontally in a vertical plane and 95 having the ends thereof secured, as at 44, to one side or section of the sleeve 3. The chain 37 passes through a vertical slot or opening 44 in said sleeve and works within the groove 16 of the barrel, the bottom of said 100 groove being corrugated, as at 54, to accommodate the feed chain.

The shells are supplied to the lower run of the feed chain which moves toward the barrel, and for this purpose a magazine or shell holding device 45 is provided, the same being of arcuate form and extending upwardly and forwardly from the lower run of the chain and lower portion of the guide 43, as seen in Fig. 7. The magazine 45 embodies a bottom plate 46 of arcuate cross section, and extending upwardly and forwardly from the forward side of the lower portion of the guide 43, and a plurality of arcuate guide bars 47 disposed on edge upon the plate 46 110 in vertical planes, and spaced apart properly to receive the shells therebetween. Spacing blocks 48 are secured between the upper forward ends of the bars 47, while the lower ends of the bars are disposed immediately 115 above the lower run of the feed chain. The upper rear edges of the bars 47 are provided with ribs 49 between and spaced from the sides of the bars 47 and providing rabbets in which the ejector flanges or beads of the 120 shells are movable. The shells 50 are inserted downwardly between the bars 47 so that their flanges or beads seat upon the upper edges of said bars, and the shells then slide down said bars, turning from a verti- 125

130

cal to a horizontal position when moving from the upper to the lower ends of said bars. The slots between the bars can be completely filled with shells, and the magazine has a large capacity, depending upon the number of bars 47 employed, and the lengths of the bars, which can be of various proportions. When the shells are inserted between the bars 47, they slide downwardly along the upper edges of said bars by gravity, and the shells drop from the lower ends of the bars into the recesses 42 of the feed chain. A plate 51 of arcuate cross section is disposed in rear and above the bars 47, being spaced from the upper edges of said bars, to hold the shells between and guide them for movement along the bars 47, and a cover plate or lid 52 is hinged, as at 53, to the upper edge of the plate 51 to swing over and close the mouth of the hopper above the upper terminals of the bars 47 when the magazine is filled. Said cover plate 52 can be swung open for inserting the shells, and when swung open, as illustrated in dotted lines in Fig. 7, provides a hopper in which the shells can be dumped to drop into place between the bars 47.

The empty shells drop from the upper run of the feed chain as it leaves the barrel, and as a means for delivering the empty shells from the machine a block 55 is disposed in the slot 44' above the lower run of the belt and fits the barrel. The block has an inclined surface 56 to receive the shells as they drop from the barrel, and deliver the shells to the rear. The lower surface of the block 55 holds the shells in the recesses 42 when moving from the magazine to the barrel.

Behind the breech of the barrel is disposed an annular cam 57, which is bolted or otherwise fastened to the rear end of the sleeve 3. This cam 57 is provided with an annular slot 58 receiving the rear ends of the members 21, and the cam 57 is provided at the outer and inner sides of the slot 58 with cam grooves 59 in which the rollers 33 of the members 21 operate. The shells, with the gun as illustrated, are fired at the left hand side of the barrel, the shell magazine and feeding means being located at the right hand side of the barrel, and the cam grooves 59 are therefore offset forwardly, as at 60, at the left hand side, whereby the rollers 33 in moving along the forwardly offset portions 60 of the grooves 59 will first move the members 21 forwardly and then rearwardly. The other portions of the grooves 59 are spaced rearwardly from the breech end of the barrel to hold the members 21 in retracted position. The grooves 59 are provided at the intermediate portion of the forwardly offset cam portion 60 with a cam 61 at the left hand side of the slot 58 and the recess 62 at the right hand side of said slot opposite the cam 61. As the members 21 are

moved to firing position, they are not only moved forwardly, but are turned or oscillated by the engagement of the rollers 33 with the cam 61 for locking the members 21, as will hereinafter more fully appear. The cam 57 is provided at the right hand side with a rear removable cover plate 63, which when removed exposes the members 21, whereby they can be removed for purpose of cleaning, repair or replacement. 75

The shell firing means includes a cam ring 65 secured upon the breech end of the barrel and having an annular series of cams 65 projecting rearwardly and working within an annular slot 66 with which the cam 57 is provided. The cam 57 is provided at the left hand side with a longitudinal slot 67 receiving the free end of a hammer 68 for striking the firing pins from the rear. Said hammer 68 is disposed above a horizontal shelf or bracket 70 carried by the sleeve 3 or other support at the left hand side, and the left hand end of the hammer 68 is pivoted, as at 71, upon the bracket 70, whereby the hammer can swing forwardly 85 and rearwardly. The hammer is provided with a roller 69 near its free end engageable with the cams 65, whereby as the barrel is rotated, the cams 65 will force the hammer 68 rearwardly, and then release the member 90 so that it swings forwardly to strike the respective firing pin at the proper time. The hammer is thus oscillated by the rotation of the barrel, there being one cam 65 for each member 21. 100

The hammer 68 is spring pressed to swing forwardly with sufficient force to fire the shells. A member 72 carried by the bracket 70 has a guide 73 in which the guide roller 74 of the hammer 68 works, to guide the hammer for proper forward and backward movement, and a pin 75 is slidable through the member 72 and has its rear end pivoted, as at 76, to the hammer. The stem 75 projects forwardly, and a coiled wire expansion 105 spring 77 surrounds the stem 75 and is confined between the member 72 and a nut 78 or other adjustable element upon the forward stem. The nut 78 can be adjusted to regulate the tension of the main hammer 110 spring 77, said spring tending to move the stem 75 forwardly to swing the hammer likewise. 115

When the gun is not operated at a great speed, the spring 77 will be sufficient for 120 operating the hammer, but when great speed is desired, it is essential to provide for the quicker movement of the hammer after release by the cams 65. For this purpose, the bracket 70 has an ear 79 through which a stem 80 is engaged adjustably, to limit the movement of the hammer 68 rearwardly by the cams 65, so as to prevent the excessive rearward movement of the hammer due to the quick motion of the cams 65. 130

The stem 80 can be threaded or otherwise engaged adjustably through the ear 79, and a jam nut 82 can be threaded upon the stem 80 for holding it in any adjustment. A coiled wire auxiliary hammer spring 81 surrounds the stem 80 and projects therefrom to act as a buffer to be engaged by the hammer when it is forced rearwardly by the cams 65, and to assist in throwing the hammer forwardly quickly, when greater speed is desired.

As a means for rotating the barrel manually, a bevel gear 83 is secured to the breech end of the barrel and is located within the cam 57, and the bevel gear 83 meshes with a bevel gear 81 secured upon the right hand end of a transverse shaft 85 journaled upon the bracket 70. A hand crank 86 is secured to the left hand end of the shaft 85 to be operated manually, although it is to be understood that the barrel can be rotated mechanically instead of manually if desired.

The shaft 85 also operates a pump for circulating water through the barrel, and for this purpose a longitudinal shaft 87 is journaled upon the bracket 70 and is connected by bevel gears 88 with the shaft 85, the shaft 87 having a crank 89 which is connected by a pitman 90 with the piston of a cylinder 91 suspended from the bracket 70. Hose sections or flexible tubes 92 connect the inlet and outlet of the cylinder 91 with the pipes 13 and 14, whereby as the shaft 85 is rotated, the piston of the pump is operated for circulating water through the barrel to keep it cool.

The operation of the gun is as follows:— As the barrel is rotated by rotating the shaft 85, the water circulating pump is operated for circulating water through the barrel, and the feed chain is operated, so that its lower run moves under the magazine toward the barrel. The feed chain in moving under the magazines will bring the empty recesses 42 below the bars 47, and the shells will therefore drop from the magazine into the recesses 42, so that the shells are carried with the feed chain to the barrel, and the barrel serving to actuate the feed chain. The shells in being brought into the groove 16 of the barrel at the bottom thereof, bring the ejector flanges or beads of the shells into engagement with the lips or hooks 27, in front of the members 21. Then as the links 38 are moved upwardly at the left hand side of the barrel, the members 21 are moved forwardly due to the travel of the rollers 33 in the cam grooves 59, and the members 21 being slid forwardly will force the shells from the recesses 42 into the rifle bores 15. Just before each member 21 reaches firing position, the shell being completely moved into the rifle bore 15, one of the rollers 36 of the member 21 engages

the auxiliary cam 61, so that the feathers 65 22 which have been moved into enlargement or chamber 24, will be turned with the member 21 to engage and abut the rear shoulder formed by the enlargement 24, thus locking the member 21 against rearward movement to hold the shell in place during the firing thereof, and to prevent the displacement of the shell by the recoil. At the time that the member 21 is moving to firing position, the hammer 68 is being cocked by being moved rearwardly by the respective cam 65, and when the member 21 reaches firing position, the hammer is released and moves forwardly by spring tension, striking the rear end of the respective firing pin 25 and forcing it forwardly so as to fire the shell. Then, as the member 21 is moved away from firing position, the hammer is cocked for the next operation, the firing pin 25 being retracted under the influence of its spring 30, and as the member 21 is moved to the top of the barrel, it is retracted, the lip or hook in engaging the shell withdrawing or ejecting it from the rifle bore 15 and again placing it in the recess 42 of the respective link or block 38. The empty shells are thus returned into the recesses 42 of the feed chain, and as the feed chain leaves the barrel at the top thereof, the shells drop into the hopper or chute 55 and are discharged from the machine. The operation is continuous, the shells being carried to firing position in succession, and being fired one after the other as long as the shells are supplied to the feed chain from the magazine. It will be apparent that as the members 21 leave firing position, they are rotated back to normal position by the engagement of the rollers 36 with the cam recess 62, in order that the members 21 can be withdrawn rearwardly, the feathers 22 moving into the channels 23, to prevent the turning movement of the members 21 in their bores 20 at any position of said members excepting firing position.

Having thus described the invention, what is claimed as new is:

1. A machine gun embodying a rotatable barrel having an annular series of rifle bores, an endless feed chain for conveying shells to and partially around with the barrel, and means for moving the shells from the chain into said bores for firing and then withdrawing the shells from said bores while the shells are being carried around with the barrel.

2. A machine gun embodying a rotatable barrel having an annular series of rifle bores, an endless feed chain for conveying shells to and partially around with the barrel, means for moving the shells from the chain into said bores for firing and then withdrawing the shells from said bores

while the shells are being carried around with the barrel, and means for firing the shells when moved into said bores.

3. A machine gun embodying a rotatable barrel having an annular series of rifle bores, a guide at one side of the barrel, a continuous shell feed member movable around said guide and barrel to feed the shells to and move them partially around with the barrel, and means for supplying shells to the feed member during its movement along the guide.

4. A machine gun embodying a sleeve, a barrel rotatable therein and having an annular series of rifle bores, a guide carried by said sleeve at one side of the barrel, an endless shell feeding chain movable around said guide and around the barrel, having shell-receiving recesses for feeding shells to and partially around with the barrel, and a magazine for supplying shells to said recesses during the movement of the chain along the guide.

5. A machine gun embodying a sleeve, a barrel rotatable therein having an annular series of rifle bores, a U-shaped guide having its ends secured to the sleeve, said sleeve having openings, and an endless feed chain movable along said guide and around the barrel through said openings for carrying shells to and partially around with the barrel.

6. A machine gun embodying a rotatable barrel having an annular series of rifle bores, a shell-feeding member extending from one side to and partially around the barrel for feeding shells, means for supplying shells to the feed member during its movement toward the barrel, and means for moving the shells from the feed member into said bores for firing and then withdrawing the shells from the bores back into said feed member during the movement of the barrel and feed member.

45 7. A machine gun embodying a rotatable barrel having an annular series of rifle bores, a continuous shell-feeding chain extending to one side of the barrel and partially around the same, said chain having shell-receiving recesses, a magazine for supplying shells to said recesses during the movement of the chain, and means for moving the shells from said recesses into the bores for firing and then withdrawing the shells from the bores back into said recesses during the movement of said barrel and chain.

8. A machine gun embodying a barrel, an endless feed chain for carrying shells to the barrel having inner recesses for receiving shells, and means for supplying shells to said recesses.

9. A machine gun embodying a barrel, an endless feed chain having a lower run moving toward the barrel for feeding shells

thereto, said chain having inner shell recesses, and means for dropping shells into said recesses at the lower run of the chain.

10. A machine gun embodying a barrel, an endless feed chain having a lower run 70 movable toward the barrel for feeding shells thereto, said chain having inner shell recesses, and a magazine above the lower run of the chain for dropping shells into said recesses.

75 11. A machine gun embodying a barrel, a magazine embodying spaced parallel bars extending upwardly and curved to one side for receiving shells therebetween at their upper ends and for guiding the shells downwardly, a plate above said bars for holding the shells therein, and a feed member movable under said bars for receiving the shells therefrom and conveying them to the barrel.

80 12. A machine gun embodying a barrel, a magazine comprising spaced parallel bars disposed in vertical planes and extending upwardly and curved to one side to receive shells therebetween at their upper ends, the upper edges of said bars having ribs and 90 being adapted to guide the flanges or beads of the shells, a curved plate spaced from said edges of the bars to hold the shells therebetween during the downward movement of the shells, a cover plate hinged to 95 the aforesaid plate to swing over the upper portions of said bars and swingable away from the bars to provide a hopper for receiving the shells so that they drop between the bars, and a feed member movable 100 under the lower ends of said bars to receive the shells therefrom and convey them to the barrel.

13. A machine gun embodying a rotatable barrel having an annular series of rifle 105 bores, an endless feed chain movable around and extending to one side of the barrel, said feed chain having a lower run moving toward the barrel and an upper run moving away from the barrel, the empty shells dropping 110 from the upper run of the chain, and means for supplying shells to the lower run of the chain.

14. A machine gun embodying a rotatable barrel having an annular series of 115 rifle bores, members movable around with the barrel and movable forwardly and rearwardly for moving the shells into and out of the bores, said members when moved forwardly being movable into locking position 120 for locking the shells in the bores, means for conveying shells to and partially around with the barrel in rear of the bores, and means for moving said members forwardly and rearwardly and for moving said members when moved forwardly to lock the shells in the bores during the firing thereof.

15. A machine gun embodying a rotatable barrel having an annular series of 125 rifle bores, members movable around with 130

the barrel and movable forwardly and rearwardly for moving the shells into and out of the bores, said members when moved forwardly being movable into locking position 5 for locking the shells in the bores, means for conveying shells to and partially around with the barrel in rear of the bores, means for moving said members forwardly and rearwardly and for moving said members 10 when moved forwardly to lock the shells in the bores during the firing thereof, firing pins assembled with said members, and means for striking the firing pins when the shells are locked in the bores.

15 16. A machine gun embodying a rotatable barrel having an annular series of rifle bores, means for conveying shells to and partially around with the barrel in rear of said bores, longitudinally slidable members carried by the barrel in rear of said means and engageable with the shells to move them forwardly and rearwardly into and out of said bores, the barrel and said members having co-operating means whereby said members when moved forwardly can be turned into locking position for holding the shells in the bores, and means for moving said members forwardly and turning them to locking position and then turning 30 the members to unlocking position and moving them rearwardly.

17. A machine gun embodying a rotatable barrel having an annular series of rifle bores, means for conveying shells to and partially around with the barrel in rear of said bores, longitudinally slidable members carried by the barrel in rear of said means and having shell engaging means at their forward ends, the barrel having longitudinal featherways and chambers at the forward ends thereof providing shoulders, said members having feathers movable in the featherways when the members are moved rearwardly, the feathers being movable into said chambers to engage the shoulders for locking the members when moved forwardly, and means for moving said members forwardly and turning them into locking position and then turning said 50 members backwardly and moving them rearwardly.

18. A machine gun embodying a rotatable barrel having an annular series of rifle bores, means for conveying shells to and partially around with the barrel in rear of said bores, longitudinally slidable members carried by the barrel in rear of said means and having shell engaging means at their forward ends, the barrel having longitudinal featherways and chambers at the forward ends thereof providing shoulders, said members having feathers movable in the featherways when the members are

65 moved rearwardly, the feathers being movable into said chambers to engage the shoulders for locking the members when moved forwardly, means for moving said members forwardly and turning them into locking position and then turning said members backwardly and moving them rearwardly, spring pressed firing pins slideable in said members, and means for striking the firing pins when said members are moved forwardly and turned to locking position.

70 19. A machine gun embodying a rotatable barrel having an annular groove and rifle bores extending rearwardly to said groove, an endless feed chain movable in said groove for carrying shells to and partially around with the barrel in rear of said 80 bores, longitudinally slideable members carried by the barrel in rear of said groove and shell engaging means at their forward ends, the barrel and said members having co-operating means whereby said members in being moved forwardly and rotated are locked against rearward movement, and a cam in rear of the barrel having means receiving the rear ends of said members, said members and cam having co-operating means 90 whereby the members are moved forwardly and then turned into locking position for firing and then turned backwardly and moved rearwardly.

95 20. A machine gun embodying a rotatable barrel having an annular groove and rifle bores extending rearwardly to said groove, an endless feed chain movable in said groove for carrying shells to and partially around with the barrel in rear of said 100 bores, longitudinally slideable members carried by the barrel in rear of said groove and shell engaging means at their forward ends, the barrel and said members having co-operating means whereby said members in being moved forwardly and rotated are locked against rearward movement, a cam in rear of the barrel having means receiving the rear ends of said members, said members and cam having co-operating means whereby 110 the members are moved forwardly and then turned into locking position for firing and then turned backwardly and moved rearwardly, spring pressed firing pins slideable in said members, a hammer for striking said 115 pins, and means operated when the barrel is rotated for operating the hammer to strike the pins when the respective members are in locked position.

120 In testimony that I claim the foregoing as my own, I have hereto affixed my signature in the presence of two witnesses.

VAUGHN STODDARD.
